HANDLING METALLIC SHEETS

Filed Oct. 23, 1929

2 Sheets-Sheet 2

UNITED STATES PATENT OFFICE

CLYDE BURGESS, OF ASHLAND, KENTUCKY, ASSIGNOR TO THE AMERICAN ROLLING MILL COMPANY, OF MIDDLETOWN, OHIO, A CORPORATION OF OHIO

HANDLING METALLIC SHEETS

Application filed October 23, 1929. Serial No. 401,928.

My invention is addressed to a method and means for handling metallic sheets at the close of a cold rolling operation, and is particularly useful in the handling of highly finished sheets such as drawing stock for automobile bodies and fenders.

Hitherto the handling of sheets after cold rolling has involved a number of steps separated both in time and place. In one mill, as an exemplary procedure, when the sheets came through the last stand of cold rolls they were conveyed therefrom on a driven belt conveyor. Two men lifted the sheets from the conveyor as they came through and piled them carefully at one side. They were then picked up by an overhead crane in lifts of approximately 15,000 pounds, and carried to a roller leveler where two men loaded them onto a driven belt conveyor feeding into the machine, and two more lifted them from a conveyor on the exit side and piled them on a truck. This truck was then hauled by a battery tractor to an oiling machine comprising four or more canton flannel rolls kept saturated with oil. At this point two more men lifted the sheets onto a driven belt conveyor feeding into the oiling machine; but the machine itself piled the oiled sheets upon a truck. This could be done because the surface film of oil protected the highly finished sheets from damage in sliding one over the other. It was not possible to have the roller leveler pile the sheets dry, without damage to the surface of the sheets.

Thus, three distinct and separated operations were carried on: cold rolling, roller leveling, and oiling. In addition there was one transfer by the use of an overhead crane, and one transfer by a battery tractor, before the sheets were ready to go to the inspector. Exclusive of those employed in the rolling, and the operators of the crane and tractor, it took eight men to handle the sheets, and the sheets were piled three times.

It is an object of my invention to carry on all three of these operations without the use of any manual labor, and in one place, effecting savings in direct labor, floor space, and crane and tractor service.

It is an object of my invention to carry

on these operations continuously, with an uninterrupted sheet travel.

It is a further object of my invention to eliminate a separate oiling machine and to do away with a number of conveyors and drives, thereby saving in cost of equipment.

It is still a further object of my invention to provide a novel sheet handling mechanism.

These and other objects of my invention which I shall point out hereinafter or which will be apparent to one skilled in the art upon reading these specifications, I accomplish by that certain construction and arrangement of parts of which I shall now describe an exemplary embodiment, it being understood that modifications may be made in it without departing from the spirit of my invention. Reference is made to the drawings which accompany these specifications.

In the drawings:—

Figure 1 is a semi-diagrammatic illustration of the end of a stand of rolls showing the leveler, conveyors and automatic piler.

Figure 2 is a view of a part of the piling mechanism showing the conveyor and skids in section, and the side guides in elevation.

Figure 3 is an elevation of the piling mechanism with a part sectional view of the leveler.

Figure 4 shows the rack member used in positioning the back stop.

In the practice of my invention, the sheets, after passing through the last stand of cold rolls 1, are carried by a driven belt conveyor 2 directly into a roller leveler 3. Oil is supplied to the first two or three rolls 4 of the leveler by means of a drip or spray pipe 5, or other suitable means, from a tank 6. The oil is deposited upon the sheets as they pass through the rolls, and onto the lower rolls of the leveler in the intervals between sheets. The remaining rolls of the leveler serve to distribute the oil evenly over the entire sheet surface on both top and bottom. The sheets thus oiled can be piled by the roller leveler without damage to their surfaces.

For the purpose of receiving the sheets as piled, and facilitating their removal without interrupting the process, I provide the mechanism next to be described. I provide an in-

clined gravity conveyor 7, having air brakes 8 and 9, or some other means for retarding the movement of materials thereover. A skid to receive the sheets rests on the conveyor, and may conveniently comprise two channels 10 with timbers 11 laid or bolted upon them. To stop the sheets from going too far and to make a neat pile endwise, I use a collapsible stop 12. This stop may be made in any form desired; but is demountable to permit the passage of the stacked sheets down the conveyor. In the embodiment shown, I provide a channel 13 fixed centrally of the conveyor, and having notches 13a in its upper portion forming a rack. This member is shown in Figure 4, and comprises the channel rack 13, and a rod or strap 30 of metal affixed thereto at one end, and turned over at the other to form a hook 31 which engages over a cross member of the roller-leveler frame as at 32. The stop proper 12, comprises a member of angle irons against which the sheets may strike. The lower part has a base 14 held to the angles by a bracket 15. A rod 16a engages a notch in the channel so as to fix the stop in position. It is held to the base by a pivoted link 16, and the stop is braced by pivoted locking levers 17 and 18. The stop can thus be released by pulling upwardly on a rod 19, breaking the joint in the locking levers; and it can then be lifted out of the way.

Side guides are provided having bases 20, guide members 21, and connecting brackets 22. Channels 23, also notched so that the spacing of the guides can be varied, are fastened in place on either side of the conveyor, and the bases of the guides are formed to engage these notches. The guides may have plates 27 affixed to them.

When a pile of sheets, say of from 15,000 to 20,000 pounds, has been formed between the guides 21 and against the collapsible stop 12, the stop is removed by pulling up the rod 19 so as to release it, and then lifting the entire stop out of the way. The air brake 8, which, during the piling operation has been applied to the under side of the rolls of the gravity conveyor, is released, and the pile of sheets, riding on the skids, rolls down to the far end of the conveyor where its travel is arrested by the brake 9. Thus room is made for a new pile of sheets; a new pair of skids is placed in position, the collapsible stop re-adjusted, and the piling continues. At some time during the formation of the second pile of sheets, an overhead crane removes the first pile from the end of the conveyor.

Having thus described my invention, what I claim as new and desire to secure by Letters Patent, is:—

1. In sheet metal apparatus, cold rolls, a conveyor, a roller leveler and means for feeding oil upon the faces of the rolls therein, and a device for forming metallic sheets into a

pile, said devices arranged serially for the uninterrupted movement of said sheets.

2. In sheet metal apparatus, cold rolls, a conveyor, a roller leveler with means for feeding oil upon the faces of the rolls therein, and a device for forming metallic sheets into a pile, said devices arranged serially for the uninterrupted movement of said sheets, said pile forming device comprising side guides, and a stop, said stop releasable to permit its removal, and means to convey away a pile of sheets.

3. In sheet metal apparatus, a device which feeds sheets and means for forming a pile thereof, said means comprising a conveyor, side guides, and a stop located above said conveyor, and comprising a support, an upright member, releasable means for bracing said upright on said support, and controlling means for said conveyor.

CLYDE BURGESS.
